OUTDOOR ADVERTISING STRUCTURE

Filed Sept. 17, 1929

UNITED STATES PATENT OFFICE

GEORGE D. OVERHOLTZ, OF LEETSDALE, PENNSYLVANIA, ASSIGNOR TO RITER-CONLEY MANUFACTURING COMPANY, OF PITTSBURGH, PENNSYLVANIA, A CORPORATION OF PENNSYLVANIA

OUTDOOR ADVERTISING STRUCTURE

Application filed September 17, 1929. Serial No. 393,189.

This invention relates to improvements in outdoor advertising structures of the character embodying a steel framework, a poster panel construction supported by the framework, and a lattice structure associated therewith. The present invention particularly relates to a new and improved lattice construction and to means for mounting and supporting the lattice on the structure.

10 In outdoor advertising structures of the character stated, it is necessary to provide parts that may be readily erected and taken down; consequently, it is the practice to construct the framework of structural steel members that may be readily assembled and secured together, and to form the panel of detachable sections. The lattice structure designed to be employed with and be positioned immediately below the poster-receiving panel

15 is usually of sheet metal construction. Heretofore, the erection or the assembling of the lattice on the structure and securing it thereto in the desired position, as well as dismantling the lattice, has been the source of considerable trouble and expense.

Among the objects of the present invention are, to provide simple and efficient means for mounting and detachably securing the lattice to the structure; to provide simple hanger members adapted to be attached to the framework of the structure and having means cooperating with means on the sectional lattice whereby said lattice sections may be readily positioned and detachably secured; and to

25 provide a new and improved sectional lattice construction.

Further objects and advantages will become apparent from the following description taken in connection with the accompanying drawing, wherein:

Fig. 1 is a front elevational view of an outdoor advertising structure embodying my invention;

Fig. 2, a perspective view of the rear of two lattice sections, showing the manner of erecting;

Fig. 3, a vertical section taken on the line III-III of Fig. 1, particularly showing a hanger and the co-acting means on the lattice section;

Fig. 4, a perspective view of the rear of an end lattice section, showing the means for attaching the same to the end capping of a panel; and

Figs. 5 and 6 are perspective views showing different forms of a clip employed.

In the drawing, the poster-receiving panel is formed of several sections 2, joined edge to edge, and supported from a steel framework having uprights or posts 3 preferably formed of angle members. A decorative molding 4 is secured around the border of the panel, and includes a bottom capping member 5 and side capping members 6, the latter extending below the panel proper, as at 7. This molding and capping may be formed of wood or sheet metal, and is secured to the framework of the panel in any suitable manner.

Positioned below the panel proper, and extending between the capping extensions 7, I provide a metal lattice, generally designated A, and comprising several lattice sections B. Said lattice sections are preferably formed of sheet metal cut and bent into the shape of lattice work including, as illustrated, a plurality of vertically extending channel-like portions 8, and spaced apart openings 9 formed in the sheet between the adjacent portions 8. Said openings 9 are formed by stamping out portions of the metal and bending the portions rearwardly of the channel-like portions 8, as at 10.

An important and characteristic feature of the present invention resides in the means for mounting and detachably supporting the several lattice sections B on the outdoor advertising structure, and, as illustrated and as preferred, these means include a series of hangers C designed to be positioned on the front faces of the uprights 3. The hangers are formed of a vertically extending member 11, preferably of flat metal, and supporting members or angles 12, having flanges 13 thereof welded or otherwise secured to the member 11. The members 12 are further formed with flanges 13a extending upwardly and parallel to the member 11, said flanges being provided with slotted openings 14 adapted to receive bolts 15 to secure the hangers to

the uprights 3. Sections of angle bar 11a may be welded on the member 11 to space said member from the uprights 3 and to provide reinforcing therefor.

5 The lattice sections B, in addition to the parts above described, each includes longitudinally extending channel-like members 16 and 16a, the upper member 16 being located a slight distance below the upper edge of the 10 lattice body and the lower member 16a being positioned adjacent its lower edge. These members are preferably secured by welding them to the body or to respective rows of the inwardly projecting fins or portions 15 10. The channels 16 and 16a are flush with one end of the lattice sections, and extend beyond the other end thereof, as at 17. Slotted openings 19 are provided adjacent the ends of the channels for adjustably securing the lattice sections together.

An angle member 18 is welded or otherwise secured to the under side of the upper flange of channel member 16, at a predetermined distance inwardly from the ends thereof. 20 Similarly, the channel 16a is provided with an angle member 18a secured to the lower flange thereof. It will be noted, however, that the angle member 18a is offset or out of alignment with the angle member 18. This arrangement is very important as it permits the assemblage of the sections to be made with the least possible trouble, as hereinafter described. The angle members 18 and 18a extend rearwardly from their respective channels, and have one flange a thereof spaced away from the channel members a slight amount, as shown in Fig. 3. In some instances, the said angle members 18 and 18a are formed integral with and extend substantially the length of the respective channels 16 and 16a, and are provided with off-set openings to function similarly to the off-set members 18 and 18a.

45 It will be noted that the channel members stiffen the flexible lattice body, thus providing a very desirable construction for handling these sheet metal sections, and that the said channels and the elements carried thereby cooperate with the hangers C for mounting and securing the lattice sections to the structure.

50 Clips 20 are provided for finally securing the lattice to the panel structure. These clips are box-like, and are provided with a lattice 55 engaging member 21, a panel capping engaging flange 22, and side members 23. The member 21 is formed with a slotted opening 24 and the flange 22 is provided with an opening 25. The flange 22 is adapted to be bent, as indicated in Figs. 5 and 6, for a purpose hereinafter described.

Several of these clips 20 with their flanges 22 bent outwardly away from the side members 23 are bolted in the upper ends of the 55 vertically extending channel-like portions 8

of the lattice sections, as indicated at c, said flanges being flush with the tops of said portions. The lattice sections B and the hanger brackets C may be elevated until the flanges 22 engage the under side of the bottom capping 5, said movement being permitted by means of the slotted openings 14 of the hanger brackets. Screws or bolts 26 are entered into the openings 25 of the clips and secure the lattice to said capping. I have shown a wooden member as one form of capping, but obviously a metal capping may be used, necessitating rows of slotted openings therein for receiving the bolts 26.

70 Clips 20 are also secured in the outer ends of the lattice channels 16 and 16a of the end lattice sections, said clips having their flanges 22 bent in the direction of the side members 23, as shown in Fig. 6. Screws or bolts 27 are entered into the openings 25 75 thereof for securing said end sections to the side capping extensions 7, as particularly shown in Fig. 4.

80 When the lattice sections have been elevated and secured to the capping, the sections are securely fastened together by means of bolts and the slotted openings 19 in the lattice channels. Also, the bolts 15 of the hanger brackets may be finally tightened to 85 secure said brackets to the uprights 3.

85 In assembling the sectional lattice on the structure, assuming that the hangers C have been positioned on the respective uprights 3, one section at a time is temporarily or loosely positioned by causing the angle members 18 or 18a, or their flanges a, to engage the respective ends b and b' of the vertically extending member 11 of the lattice hanger. The length of the members 18 and 18a are such as to permit of a lateral or sliding movement of the section, and owing to the offset position of these members relatively to each other, as above described, it will be understood that the upper member 18 will be brought into engagement with the end b of 110 member 11 before the member 18a engages the end b, thus aiding in the assembling by properly guiding the section while it is being slid along.

115 Extensions 17 of the channels 16 and 16a may be telescoped in the channel ends of an adjacent lattice section, and temporarily bolted together by means of the slotted openings 19 therein.

120 Thus, it will be seen that the entire lattice may be temporarily positioned below the panel proper. By means of the slotted openings 19 of the channel 16 and 16a, the lattice may be "stretched" to fill the space between the end capping extensions 7.

125 After the temporary positioning, as above described, the lattice is finally positioned and secured in the final position by means of the clips 20 and their cooperating fastenings.

130 If desired, a molding or apron D may be

secured to the lattice sections B by means of bolts 28 and spacers 29. The apron D preferably extends beyond one end of the lattice sections for telescoping with adjacent apron portions, as will be readily understood.

5 I claim:

1. In an outdoor advertising structure, the combination with two sheet metal lattice sections each comprising a body cut and bent to form channel-like portions and openings and fins between the adjacent channel-like portions, and a reinforcing channel member secured to the body of each section and extending substantially at right angles to the said 10 channel-like portions, said reinforcing members having coating means for adjustably connecting the sections.

2. In an outdoor advertising structure, a sheet metal lattice section comprising a body 20 cut and bent to form channel-like portions and openings and fins between the adjacent channel-like portions, and a reinforcing channel member welded to the body and extending substantially at right angles to the 25 said channel-like portions, said channel member having one end projecting from the body and its other end substantially flush therewith, said ends being slotted.

3. In an outdoor advertising structure, a 30 sectional sheet metal lattice including a body cut and bent to form vertically extending channel-like portions and openings and fins between the adjacent channel-like portions, and upper and lower spaced apart transversely extending reinforcing channel members welded to the body adjacent its top and bottom, said members having slotted end 35 portions.

4. In an outdoor advertising structure, a 40 sectional sheet metal lattice including a body cut and bent to form vertically extending channel-like portions and openings and fins between the adjacent channel-like portions, and upper and lower transversely extending reinforcing channel members secured to the body, said channel members each having 45 a slotted end portion projecting from the body and the other ends of said channels being slotted and substantially flush with the body.

50 In testimony whereof I affix my signature.
GEORGE D. OVERHOLTZ.
